UNITED STATES PATENT OFFICE.

WILLIAM P. PITTS, OF INDEPENDENCE, MISSOURI, ASSIGNOR TO IRVING-PITT MANUFACTURING COMPANY, OF KANSAS CITY, MISSOURI, A CORPORATION OF MISSOURI.

BOOK-COVER ATTACHMENT.

1,017,796.

Specification of Letters Patent.

Patented Feb. 20, 1912.

Application filed November 20, 1909. Serial No. 529,043.

To all whom it may concern:

Be it known that I, WILLIAM P. PITTS, a citizen of the United States, residing at Independence, in the county of Jackson and

5 State of Missouri, have invented certain new and useful Improvements in Book-Cover Attachments, of which the following is a specification.

10 My invention relates to improvements in loose leaf books.

The object of my invention is to provide a loose leaf book which may be readily converted into a convenient copy holder.

In carrying my invention into effect I 15 provide a loose leaf book with covers that may be positioned to form legs for supporting the book in the open position, means being provided for releasably holding the covers so positioned.

20 The novel features of my invention are hereinafter fully described and claimed.

In the accompanying drawings—Figure 1 illustrates, in perspective, the preferred form of my invention, the parts being arranged to form a copy holder. Fig. 2 is an end view of the book shown in Fig. 1, the covers and brace being in the closed position. Fig. 3 is a fragmental view, partially in elevation and partially in vertical section, 30 of the brace and covers, the covers being in the folded back position. Fig. 4 is a cross section on the dotted line *a*—*b* of Fig. 3, the brace being shown extended. Fig. 5 is a view similar to Fig. 4, the brace being shown folded upon the inner side of the cover to which it is hinged. Fig. 6 is a perspective view of a modified form of my invention, the covers being shown in the folded back position. Fig. 7 is an end view of the book 40 shown in Fig. 6, the book being shown with the covers in the closed position.

Similar characters of reference denote similar parts.

1 and 2 denote the covers of the book, 45 which are preferably hinged to the back 3 so as to be swung backward to an inverted V-shaped position, in which position the covers will form legs to support the book in open position. The book is provided with 50 means for detachably supporting loose leaves, such means comprising preferably co-operating ring hooks 4, mounted on the back 3 in any ordinary manner which will permit the co-operating hooks to separate so as

to remove or insert detachable leaves 5. Re- 55 leasable means are provided for retaining the covers 1 and 2 in the positions in which they will form legs.

In the form of my invention shown in Figs. 1 to 5, I provide a brace which is 60 hinged to the cover 1 at two points located at different distances from the back 3, the brace having means for detachably engaging the opposite cover. Preferably, the brace is made of wire and has two diverging arms 6 65 and 7, which at their outer ends are turned at an angle and are hinged in plates 8 and 9, which are mounted in the cover 1. In the cover 2 is mounted an eyelet 10 into which is adapted to be inserted the wire brace, the arms 6 and 7 of said brace being resilient and compressible toward each other sufficiently to permit the passage through the eyelet 10 of a projection 11 on one of the arms. When the arms 6 and 7 have been 75 inserted in the eyelet 10 they will expand and the projection 11 will releasably hold them engaged with the eyelet 10. With a little force, however, the arms 6 and 7 may be withdrawn from the eyelet 10, after 80 which the book may be closed. The wire brace is preferably arranged so that it may be swung parallel to and at the inner side of the cover to which it is attached, as shown in Fig. 2, thereby not interfering with the 85 outside appearance of the book.

In the form of my invention shown in Figs. 6 and 7, the cover 1 has swinging from its outer edge a brace 12, preferably of cardboard, and provided at its free end 90 with a lateral transversely extending flange 13 which is adapted to engage and hold the cover 2 when the covers are swung backward to the inverted V-shaped position shown in Fig. 6. In this position the brace 12 serves also to support the covers as well as to retain them in the folded back position. It will be noted that the back 3, in the form shown in Figs. 6 and 7, is located between the covers 1 and 2 in a position such that 100 the covers must be sprung toward each other to enable the cover 2 to engage the flange 13. Preferably, either the covers or the back 3, or both, may be sufficiently resilient to effect this function. By means of this construction the cover 2 will be more firmly held by the flange 13 than would be the case if the cover 2 swung freely to a position 105

engaging said flange. Preferably, the brace 12 is arranged so as to be swung parallel to and at the inner side of the cover 1, as shown in Fig. 7.

5 I do not limit my invention to the constructions shown and described, as various modifications of my invention, within the scope of the appended claims, may be made without departing from its spirit.

10 Having thus described my invention, what I claim and desire to secure by Letters Patent, is:—

1. A loose leaf book provided with covers which may be positioned to form legs to support the book in open position, one cover having an eyelet extending therethrough, and a brace carried by the other cover and adapted to enter and releasably engage said eyelet to hold the covers so positioned.

20 2. A loose leaf book provided with covers which may be swung backward to an inverted V-shaped position, one cover having an eyelet extending therethrough, and a brace hinged to the other cover and having 25 a spring catch insertible through and compressible by said eyelet for releasably engaging said eyelet.

30 3. A loose leaf book provided with covers which may be swung backward to an inverted V-shape position, one cover having an eyelet, and a brace having two diverging arms hinged to the other cover along one side edge thereof, the brace being adapted to enter and releasably engage said eyelet.

35 4. A loose leaf book provided with covers

which may be swung backward to an inverted V-shape position, and a brace hinged to one cover and having its axis parallel with one side edge thereof, and provided with means for releasably engaging the other 40 cover to hold the covers in the inverted V shape position.

5. A loose leaf book provided with covers which may be swung backward to an inverted V-shape position, and a brace hinged 45 to one cover and having its axis parallel with one side edge thereof and having means for engaging the other cover to hold the covers in the inverted V-shape position, the brace being capable of being swung parallel 50 to and at the inner side of the cover to which it is hinged, and in the latter position not interfering with the closing of the covers.

6. A loose leaf book having covers which 55 may be positioned to form legs to support the book in the open position, and a wire brace having resilient diverging arms hinged to one cover, the other cover having an eyelet into which said arms when compressed toward each other may be inserted 60 to hold the covers releasably so positioned.

In testimony whereof I have signed my name to this specification in presence of two subscribing witnesses.

WILLIAM P. PITTS.
